Sewing Patent

The clause referred to in the Sewing Patent and making part of the same containing a description in the words of the late William Hinckley himself of his improvement in the Sewing-Set.

To all to whom these presents shall come. Be it known that William Hinckley of Utica in the County of Oneida and State of New York here invents a new and useful improvement in a Machine for setting hairs and that the following is a full and true description of the construction and operation of said Machine as invented or improved by me, the principle character or part of this machine is made of cast iron 5 inches long thick wide and of the same width thick and is called the frame or base of the machine. The edges or side corners of the frame $\frac{1}{4}$ of the frame wide in width from the corners back towards the center are beaded or taken off to make room for the hair or feet of the saw-teeth, on the edge or side of the frame the quantity beaded off is just sufficient to let hairs in the most thick middle or hair or - espay on the opposite or second edge while the quantity beaded or taken off is little more than on the first edge and on the third edge or side the quantity beaded or taken off is still more than it is on the second edge or side in so far making four gradually different inclinations or inclined planes on the edges or side corners of the frame. The each of the two opposite edges of the frame midway from the ends is ~~at an~~ ^{at an} angle projecting out so as to form a hook or knob on each side in so far as to keep the frame in its place in a kind of vice into which it is put the vice above alluded to is formed of two parts or pieces of cast iron which open like a hinge of the Capital letter D and are each 5 inches long in the straight part or about 4 inches in diameter transversely on the description of the vice the two parts in shape of the letter D are mounted with a screw to oppose and the ends D. The vice and frame may also be made of wrought iron.

or - that is of steel of cast iron will be equally as good and much cheaper. The frame should be cast of hard iron or be made of steel and hardened. The base of iron or other metal base forms the D. Should be about $\frac{1}{2}$ inch wide by $\frac{3}{4}$ ths of an inch deep, except the straight part of the under D) which should be but half an inch deep with a $\frac{1}{2}$ inch lip to the reception of the formula which is held in its place by a pin or projection running $\frac{1}{8}$ to $\frac{1}{4}$ an inch high in the back or outside of the straight part of the under D. The straight part of the upper D) may be made square and may be casted. The guide is the inner edge of the saw set to the line, on the formula from which the notches are made around the middle of the straight part of the upper D. is a kind of lever about 4 inches long made of a rod of iron of $\frac{1}{4}$ of an inch diameter, thinning out tapering down to the thickness of $\frac{1}{8}$ of an inch at the end with a thin edge and long enough to encompass the D which is made round for that purpose. It is then bent round the D. so the ends of D. are connected together about one inch from the inner edge of the formula in the circular part by a hinge at each end and set at $\frac{1}{2}$ to $\frac{3}{4}$ of an inch from the base. The machine will set. Most all kinds of straight saws in 4 different kinds of notches by shifting the formula to the side so that saws may be set on either edge or side thereof. The method of setting is to place the saw in the machine with the better side towards the hinge to let no more than the length of the teeth extend inside of the inner edge of the guide. Then fasten the saw by turning the screw by which a thicker part of the screw to loop to the screw is carried in between the parts of the saw firmly. Straining the wire apart at the two ends and compressing it at the straight part. The saw is set by placing a pin much smaller on the teeth and stretching it sufficiently with a hammer - This operation sets four inches in length on the saw when it has to be removed to much in the saw, and set as before and so on. For setting coarse saws such as nail - cropt - saw - whip - scissle saws the a machine is made of cast iron, steel or wrought iron about 6 inches long and from $6\frac{1}{4}$ to $7\frac{1}{2}$ inches square with the notches at the ends. The notches at each end on opposite sides of the wire - wire are made from $\frac{1}{4}$ to $\frac{1}{2}$ an inch in length. Then four notches

we make little if any use of rice, to be taken on our different scales, & into
which we will not go to the lowest truths respecting the power of using the
best wooden machine to place it in a bush and place the sun-tattoo
directly on the machine base and strike them with a hammer, or if the
sun is full to say. In action or shall the machine for setting sun-tattoo
be in force against the sun-tattoo will set as before the sun is taken on
discovery of every part of the machine were specified and described except
the plow which is the same that has been made by the late Mr. Michael
Hill before the knowledge of any machine being made or patented
bearing any similarity to it but from information which we recd it ap-
peared probable that a machine similar to this is being made especially the
short Culus the or scale. we patented it John Stevenson of Quincy Illinois
in 1812 in case of which the invention of the said machine is of no spe-
cial and important as claimed as an improvement. in invention
or discovery of the improvement in the different forms or contrivances
hereinafter described in which said machine may be made is also
claimed. First a different base may be made by taking a part of the
part of the tree that by turning will cause the parts of
the tree and strain them apart the same as the other base. — the parts
of the tree will strain them apart the same as the tree were — the
part of the tree may be strained apart by a nail that will run through
the part of the tree and against the other part.

Second the tree may be made by
a different form without means of fast or loose the parts of the tree
or strain together by a screw — also in the case of the former
